UNITED STATES PATENT OFFICE.

FERDINAND PAUL BAUMANN, OF KUSNACHT, SWITZERLAND.

BEATING APPARATUS.

Application filed December 9, 1920. Serial No. 429,552.

To all whom it may concern:

Be it known that I, FERDINAND PAUL BAUMANN, a citizen of the Republic of Switzerland, residing at Kusnacht, in the Canton 5 of Zurich, Switzerland, have invented certain new and useful Improvements in Beating Apparatus, of which the following is a specification.

This invention has reference to beaters or 10 beating-apparatus of the kind wherein provision is made within a housing of a rotatable drum or roller adapted to carry a series of beaters, and a cushion upon which the objects to be freed of dust and dirt are 15 placed and caused to be beaten when the drum or roller is rotated.

The characteristic and novel features of 20 my invention consist, firstly, of the particular arrangement and mounting of the beaters on the rotatable roller and, secondly, in constructing the beater housing of a bottom part which is open at the top and contains the rotatable roller, and a cover part comprising 25 two similar portions which are so connected to the said bottom part that they are adapted to be adjusted vertically and backwards and forwards in relation to the bottom part, all for the purpose hereinafter described.

The accompanying drawings illustrate 30 one desirable form in which my invention may be embodied,

Fig. 1 showing an end elevation and

Fig. 2 a side elevation of the beating apparatus with the top portions of the housing 35 in closed position.

Fig. 3 represents a longitudinal section through the apparatus;

Fig. 4 is a section through line A—A in Fig. 2;

Fig. 5 shows a side elevation of the apparatus with the cover portions of the housing 40 adjusted vertically and forward and backward respectively;

Fig. 6 is a plan of Fig. 5, and

Fig. 7 represents certain details, partly in 45 section, illustrating the manner of mounting the beaters on the roller.

Similar parts are designated by like references throughout the several views.

To carry out my invention, I make provision of a housing which in this case is of 50 rectangular section and comprises a bottom part 1 open at the top, and a cover-part formed of two similar portions 2 and 3 fitting over the open top of the bottom part. The cover portions 2 and 3 are connected to

the bottom part by means of links 4, one pair of such links being provided at each side of each of the said cover portions in such a manner, that the latter are adapted to be adjusted and brought into the position shown in Figs. 5 and 6. When desired to be held in the position illustrated in Fig. 2, these cover portions are attached together by screw-bolts mounted at 5, while a latch 6 60 renders the cover portion 3 secure against displacement. With the two cover portions in the positions shown in Figs. 5 and 6, a frame 7, having an opening 7' and cords 7" fixed across the same, is mounted between 65 and level with the top of the said cover portions with which it forms a table. Part of the front wall of the bottom part 1, namely that designated by 8, is formed into a door which is hinged to the other part 8' of such 70 wall and thus capable of being swung about its pivot, a latch 9 mounted on the portion 2 enabling the fixing in raised position of the door 8. At the front of the housing 1 and immediately below the cover portion 2 is 75 arranged a slideable window 10, and situated behind an opening 11 also provided in the front wall of the housing 1 and beneath the window 10, is a cushion 12 upon which the object to be beaten is placed. This cushion 80 may be of any convenient and known construction and arrangement.

Mounted transversely of the bottom part of the housing, and journalled in bearings 13 which are secured to the sides of the said 90 bottom part by means of angle-irons 14, is a tubular roller 15 carrying a series of beaters 16 of flexible material, for instance leather. The roller for this purpose is provided with a corresponding number of bores 95 17 which are arranged in a spiral line, Fig. 4, each bore extending through the tubular part of the roller 15 and gradually widening at one end in order to receive a sleeve 18 of corresponding shape, in the present case of 100 the shape of a bell. Each of these sleeves is riveted at its top to the roller and, in turn, serves to receive a spring 19 of which one end is attached to the roller by means of a screw 20, while the other end at or about the middle of the length of the sleeve is fashioned into a coil. Also secured at 20 and made to extend through the coil of the springs are 105 the aforementioned beaters 16.

Assuming now the roller 15 to be rotated 110 by any suitable power transmitted to the pulley 21 and the beaters swung in the direc-

tion of the arrow, Fig. 3, the resulting swinging and vibrating movement of the springs impart a spiral movement to the beaters as indicated in Fig. 4, which movement is accentuated by the play sideways of the springs 19 in the rounded-off or bell-shaped part of the sleeves 18. The beaters, at the moment of coming in contact with the cushion 12, thus actually assume the form of a spiral thereby increasing the extent and consequently the effect of each hit on the object to be beaten and cleaned. Owing to the bell-shaped form of the sleeves 18 the springs are easily guided and also safeguarded against undue strain or breakage.

It will be understood that if it is desired to treat objects too large to be introduced into the housing, for instance mattresses, the apparatus is adjusted as shown in Figs. 5 and 6 and the mattress placed on the table formed by the adjusted cover portions 2 and 3 and the frame 7. The cushion 12 is removed, the beaters then acting on the mattress from below through the opening 7 and against the cords 7".

It will furthermore be understood that the usual suction device needs to be provided for the dust to be sucked off, care having to be taken that the air current flows directly above and past the objects to be beaten so that each particle of dust is at once drawn away from such object. The suction device which, as it is not intended to form part of this invention is not shown, may be connected to and made to communicate with the housing at 22, designating the air-outlet.

Having now fully described my said invention what I claim and desire to secure by Letters Patent is:—

40 1. In the herein-described beating apparatus, the combination, with a housing consisting of a bottom part which is open at the top and a cover comprising two similar por-

tions hinged to and fitting over the bottom part; of means to secure the said hinged portions together and hold them in raised, that is, closed position; a roller journaled in the bottom part and arranged transversely of the cover portions; a series of beaters of flexible material carried by the roller and mounted in a spiral line thereon; means to adjust the aforesaid cover portions into the lower, that is, open position; and a frame adapted to be fitted between the adjusted cover portions, the said frame having a rectangular opening and cords fixed across the same and the said opening and cords being within reach of the beaters, all as and for the purpose set forth.

2. In the herein-described beating apparatus, the combination, with a housing having an opening in one of its walls, of a cover comprising two similar portions hinged to and fitting over the housing; a cushion mounted within the housing and immediately behind the said opening and adapted to receive the goods to be beaten; a roller journaled in the housing parallel to the cushion and having a series of bores which are disposed in a spiral line and gradually widened at one end; sleeves fitted in said bores; a coil-spring mounted in each of the sleeves and projecting from the widened end thereof, a beater of flexible material fitted in each spring and extending therethrough, and means to fasten one end of the springs and the corresponding end of the beater to the roller, all substantially as and for the purpose set forth.

In testimony whereof I have hereunto set my hand in the presence of two subscribing witnesses.

FERDINAND PAUL BAUMANN.
